US00D773893S

(12) **United States Design Patent** (10) Patent No.: **US D773,893 S**
(45) Date of Patent: **** Dec. 13, 2016**

(54) **BLADE COVER**

(71) Applicant: **Prince Castle LLC**, Carol Stream, IL (US)

(72) Inventors: **Mark Fastabend**, Chicago, IL (US); **Kyle Kestner**, Schaumburg, IL (US); **Anthony Caringella**, Norridge, IL (US); **Michael Graef**, Naperville, IL (US); **Julia Padvoiskis**, Chicago, IL (US); **Eric Larson**, Pecatonica, IL (US); **Scott Hammac**, Joliet, IL (US)

(73) Assignee: **Prince Castle LLC**, Carol Stream, IL (US)

(**) Term: **14 Years**

(21) Appl. No.: **29/517,817**

(22) Filed: **Feb. 17, 2015**

(51) LOC (10) Cl. **31-00**

(52) U.S. Cl.

USPC **D7/412**

CLAIM

The ornamental design for a blade cover, as shown and described.

DESCRIPTION

FIG. 1 is a perspective view of a blade cover;
FIG. 2 is a front view thereof;
FIG. 3 is a back view thereof;
FIG. 4 is a left side view thereof;
FIG. 5 is a right side view thereof;
FIG. 6 is a top view thereof; and,
FIG. 7 is a bottom view thereof.

(Continued)

The broken lines showing of various portions and other elements in the Figures are for the purpose of illustrating unclaimed portions and form no part of the claimed design.

1 Claim, 7 Drawing Sheets
